UNITED STATES PATENT OFFICE.

FREDERICK JOHN VAUX, OF LANCASTER, PENNSYLVANIA, ASSIGNOR TO MONITOR BI-LOOP RADIATOR COMPANY, OF LANCASTER, PENNSYLVANIA.

STEAM-GENERATING BOILER.

1,402,388.

Specification of Letters Patent.

Patented Jan. 3, 1922.

Application filed August 25, 1919. Serial No. 319,552.

To all whom it may concern:

Be it known that I, FREDERICK JOHN VAUX, a citizen of the United States, residing at Lancaster, in the county of Lancaster and State of Pennsylvania, have invented certain new and useful Improvements in Steam-Generating Boilers, of which the following is a specification.

This invention relates to steam generating boilers for use in connection with systems of heating houses or other buildings and has for its object the provision of a water heating boiler to produce and maintain steam by the use of a less quantity of fuel, and therefore more economically, and also a boiler requiring a small amount of attention to hold the steam pressure. To this end, the present invention comprises several new principles of construction. Among these attention may be called to the formation and arrangement of the U-shaped tubes, hereafter to be referred to as U-tubes, the economy of construction by having the water compartment extend the full length of the furnace from pit to dome and thereby constitute the fire box and walls as well as the heat compartment of the boiler, and the special type of clinker crushing grate designed for use with either hard or soft coal or wood.

The arrangement of the boiler is such that the water travel is all in a vertical direction, which is the natural direction when heated, except in the short space consumed by the easy bends of the U-tubes, and also that the fire travel is also in a vertical direction circulating through the water shell and around the U-tubes. The fire and heated gases must pass through this congregation of U-tubes twice before it reaches the flue, the heat being absorbed from these gases by direct impingement against the tubes as well as by the circulation around the tubes. Also, the construction is such that it offers no resistance to expansion or contraction as is the case in other types of boilers, and the continual circulation of the water causes an even temperature over all parts of the boiler thus the liability of this type of boiler cracking or exploding when placed under heavy strains is reduced to a minimum, if not wholly eliminated.

An embodiment of the present invention

is disclosed in the accompanying drawings, wherein:—

Figure 1, is a vertical section on the line *y*—*y* in Fig. 3. Fig. 2, is a detailed cross section of the flue check. Fig. 3, is a cross section on the line *x*—*x* of Fig. 1, looking toward the dome of the boiler. Fig. 3^A is a plan view and Fig. 4, is a cross section on the line *z*—*z* of the baffle plate used in the top of the boiler. Fig. 5, is a cross section on the line *x*—*x* of Fig. 1, looking toward the pit of the boiler.

The boiler is constructed with a heavy base *A*, preferably of cast iron which is sufficiently tall to insure a proper draft under the fire, and to give ample room for an ash pit. The base *A*, has mounted thereon a hinged door *a*, for the control of the draft and also for the removal of the ashes, in a well known manner. Mounted in this base *A*, is the grate, consisting of the grate bars *B*, (Figs. 1 and 5) having the intermeshing projections *b*. As will be seen from Fig. 5, this bed of intermeshing projections constitutes an almost solid bed for the fire. Each grate bar has a reduced end *c*, mounted to turn in a socket *d*, in the pit or base *A*, an extension *e*, which freely turns in corresponding openings in the pit *A*, not shown, but of usual construction. The extensions *e*, are designed to be turned by the handle *f*, so that upon each pull of this handle the slag and clinkers will be crushed and loosened so that the grate is effectively and readily cleared. The upper rim or periphery of the pit *A*, has a groove *A'* into which fits the annular ring *C*. Upon this base *A*, is fit a double walled water shell *D*. The inner and outer walls have a water tight fit over the annular ring *C*, and are bolted to this ring as shown at *E*, in Fig. 1. This water shell is constructed of what is known as flanged, fire-box steel, and it extends the full length of the boiler from the pit *A*, to the dome *F*. The dome *F*, also has secured thereto an annular ring *G*, to which the shell is bolted as at *H* (Fig. 1).

The one side of the shell *D*, which will be called the face of the boiler, has a hinged door *I*, through which fuel is supplied to the boiler, and also there are the usual draft regulating slides *g*. The opening in the water shell for the frame of the door *I*, is

appropriately closed, as shown at J, in Fig. 1. Water is introduced into the lower part of the shell D, opposite the fire-box through the pipe K (Figs. 1 and 5). The inner wall 5 of the shell D, has suspended therefrom a series of U-shaped tubes L and M, Figs. 1, 3 and 5, the ends of which have water tight connection with the inner wall of the shell D, as shown at h, and i, respectively. It will be 10 noted that tubes L, are longer than tubes M, and that they are alternately arranged on the interior of the boiler, except over the door I, where all of the tubes must necessarily be short. These tubes radiate inwardly toward 15 the center of the boiler, the longer tubes L, extending further into the interior of the boiler than the shorter tubes M. The outer wall of the shell D, is equipped with plugs j, Figs. 1, 3 and 5, which plugs are opposite 20 each of the open ends of each of the U-tubes L and M. The purpose of these plugs is to facilitate easy removal and repair of the tubes should there be any accident to any one of the tubes.

25 As will be apparent from Fig. 1, the lower part of the water shell D, constitutes the fire box of this boiler-furnace, and that the heat gases must, in escaping to the flue, first strike the lower curves of the U-tubes, pass along 30 these tubes and circulate in between, and again strike the upper curves of the tubes before passing out of the water shell. At the same time, the unheated water which enters near the base of the shell is heated and rises, 35 as it expands, not only in the water shell D, which surrounds the fire, but also flows in the lower end of the U-tubes L and M, and out through the upper end. In the course of this travel the water is heated to such an extent 40 that it becomes the steam vapor that travels through the supply pipe leading to the radiators throughout the building which are to be heated. Thus, the water flows in the same direction as the heat gases, namely in a vertical 45 direction, and as both are following their natural courses.

To further assist in the circulation of the heat gases through the tubes L and M, the dome F, of the boiler-furnace is fitted with a 50 baffle plate N, best shown in Fig. 4, but shown applied in Figs. 1 and 3. As will be seen from Fig. 4, it consists of a solid central portion of a smaller diameter than the interior 55 diameter of the furnace, from which extends outwardly the prongs k, each of which has a hole l, through which bolt m, passes to secure

the baffle plate in position in the boiler above the U-tubes. The top of the dome F, is ventilated to the flue or chimney (not shown) as at O, in Fig. 1. This opening is controlled 60 by the check valve n, pivoted at n', having a curved ratchet arm o, cooperating with a slot p, in the dome F, to adjust and regulate the amount of draft. This draft is, like other furnaces, used to regulate the fire when it is 65 desired to accelerate or increase the amount of heat generated. To further assist in the drawing power of this connection with the flue, the upper part of the dome F, above the check valve n, is ventilated to the atmosphere, as shown at P, in Fig. 1. This auxiliary opening P, is closed by the hinged valve q, and has fastened to it a chain r, which extends around within convenient reach of the person attending to the furnace, so that it 70 may be opened and closed entirely at will. Thus, it will be seen that the heated gases passing from off the fire necessarily pass through the tubes L and M, because the only way for them to get to the flue is on the outside of the solid central portion of the baffle plate N, between the prongs k.

The steam vapor is supplied to the building to be heated through the pipe Q, and the water of condensation returns to the boiler in 85 a well known manner, through the pipe R. All of the pipes K, Q and R, have water tight connections with the outer wall of the water shell D. It sometimes becomes necessary to 90 reduce the steam pressure and to this end the outer wall of the water shell D, is provided with a surface blow-off valve S.

I claim:

The steam generating boiler furnace herein described, consisting of a base having an 95 annular channel in its upper edge, a grate in said base, a water shell having an annular ring in its lower portion fitting the annular channel of the base, an annular ring fitting the upper end of said shell, a dome mounted 100 on the shell and secured to said ring, a concaved baffle plate having a series of perforated ears secured between the dome and ring, the securing means passing through said dome, ears and rings, heat regulating 105 means in said dome, and a series of U-tubes disposed vertically between the baffle plate and grate and communicating at each end with said water shell.

In testimony whereof I hereunto affix my 110 signature.

FREDERICK JOHN VAUX.
